United States Patent Office

Des. 181,454
Patented Nov. 19, 1957

181,454

SPRAY CONTAINER

John Frederick Becker, Vineland, N. J., assignor to Helene Curtis Industries, Inc., Chicago, Ill., a corporation of Illinois

Application August 1, 1956, Serial No. 42,483

Term of patent 14 years

(Cl. D58—8)

Fig. 2

The lining on the drawing represents contrasting colored areas. The rear and sides not shown are substantially the same as the front shown.

I claim:

The ornamental design for a spray container, substantially as shown and described.
